G. W. CASSIDY,
HOOD OR SHADE FOR A LAMP,
APPLICATION FILED JUNE 8, 1918.

Reissued Aug. 27, 1918.

14,511.

Inventor:
George W. Cassidy
By his Attorney
Edmund Cooper Brown

UNITED STATES PATENT OFFICE.

GEORGE W. CASSIDY, OF NEW YORK, N. Y.

DESIGN FOR A HOOD OR SHADE FOR A LAMP.

14,511.

Specification of Reissued Design. Reissued Aug. 27, 1918.

Original No. 51,255, dated September 11, 1917, Serial No. 183,374, filed July 28, 1917, for 7 years. Application for reissue filed June 8, 1918. Serial No. 238,998. Term of patent 7 years.

To all whom it may concern:

Be it known that I, GEORGE W. CASSIDY, a citizen of the United States, and a resident of the borough and county of Queens, in the city and State of New York, have invented a new, original, and ornamental Design for Hoods or Shades for Lamps, of which the following is a specification, reference being had to the accompanying drawings, forming 5 part hereof.

In the said drawings Figures 1 and 2 are perspective views of the front and end respectively of a hood or shade showing my new design.

I claim:

15 The ornamental design for a hood or shade for a lamp, as shown.

In witness whereof I have hereunto signed my name this 18th day of May, 1918.

GEORGE W. CASSIDY.
